US00D998490S

(12) United States Design Patent (10) Patent No.: US D998,490 S
(45) Date of Patent: * Sep. 12, 2023

(54) WATCHBAND

(71) Applicant: Xiaotao Yin, Shaoyang (CN)

(72) Inventor: Xiaotao Yin, Shaoyang (CN)

(73) Assignee: Xiaotao Yin, Shaoyang (CN)

() Term: 15 Years

(21) Appl. No.: 29/873,223

(22) Filed: Mar. 28, 2023

(51) LOC (14) Cl. 11-01

(52) U.S. Cl.
